UNITED STATES PATENT OFFICE.

AUGUST KAZENMAIER, OF STUTTGART, GERMANY, ASSIGNEE, BY MESNE ASSIGNMENTS, TO AMERICAN BOSCH MAGNETO CORPORATION, OF NEW YORK, N. Y., A CORPORATION OF NEW YORK.

AUTOMATIC ELECTRIC REGULATING DEVICE.

1,331,815.

Specification of Letters Patent. Patented Feb. 24, 1920.

Application filed October 28, 1918. Serial No. 260,056.

To all whom it may concern:

Be it known that I, AUGUST KAZENMAIER, engineer, a subject of the German Emperor, residing at and whose post-office address is 5 Stuttgart, Mühlrain 9/1, Germany, have invented certain new and useful Improvements in Automatic Electric Regulating Devices; and I do hereby declare the following to be a full, clear, and exact description of the invention, such as will enable others skilled in the art to which it appertains to make and use the same.

In known regulators in which the alterable resistance of the exciting circuit of 15 electric machines (dynamos, motors) consists of a pile of conducting bodies, such as carbon granules for example, which are subjected to differences of mechanical pressure, electromagnets have hitherto been employed 20 for moving the plate that bears upon the pile, the armatures of which are separated from the active pole surface of the magnet by an air gap of differing magnitude. With such magnets, the more the armature is 25 attracted, the smaller the air gap becomes, and thus the attractive force increases, in accordance with the known law, in a degree inversely proportional to the square of the distance. But the regulating process requires that the attractive force of the armature shall be as nearly as possible proportional 30 only to the electric excitation or energization of the magnet and practically independent of other influences, for then only 35 will the pressure exerted upon the pile of granules alter in strict accordance with the fluctuations of the magnitude (potential, current) that is to be regulated. Now differences of the air gap between the armature 40 and the pole of the electromagnet will, with one and the same degree of change in the value of the electric excitation, give rise to attractive forces of different values. Thus, if the distance between the armature 45 and the pole is small, a very small increase of magnetization will suffice to powerfully lift the armature away from the piled bodies of granules, and if the distance is large a motion of the armature will only result 50 if a very considerable change of the magnetization takes place. Therefore if, in a stable condition of the regulator, the dis-

tance of the armature from its pole differs, the sensitiveness of the regulator will also differ, and the regulating operation is un- 55 favorably affected.

The condition that the pressure exerted upon the pile of granules shall, as far as possible, depend only on the changes of the magnitude to be regulated, will thus be 60 fulfilled by the electromagnets hitherto employed, only if the surface of the pile of granules is always at one and the same distance from the pole surface of the magnet; for since the pressure plate is rigidly coupled with the armature, the air gap between the armature and the pole surface can be 65 kept constant in a stable condition of the regulator only if the said distance between the granules and the pole surface remains 70 the same. But this demand is difficult to fulfil, because, in consequence of the vibration of the vehicle in which the machine is mounted, or of the suction caused by the armature on a sudden increase of the mag- 75 nitude to be regulated, the granules tend to shift their positions and to pile up on one side only. Attempts have been made to remove this drawback by subdividing the pile of granules or by similar devices, but a 80 disadvantage of these arrangements is that, in addition to imperfect action, they render the regulator more complicated.

The object of this invention is to remove the drawbacks herein before described. 85

This object is accomplished by arranging the pile of granules with respect to the plate by which they are compressed, in such manner that the plate (in spite of a comparatively large distance of movement, within 90 the known limits between which the core of the solenoid exerts a practically constant attractive force upon the plate) may assume any position with respect to the pile, without the attractive force of the relay, presuming that its energization remains constant, being changed, so that a change of resistance 95 of the pile of granules is produced which is as nearly as possible proportional to the magnitude to be regulated.

It is known that the forces of attraction exerted by an electromagnet or solenoid on its armature or core—if these forces are 100 graphically shown in their relation to the

corresponding distances between the center of the solenoid and the core, these distances being marked along the abscissæ—are represented by a curve which ascends from zero 5 to a maximum value and then descends again to zero. This curve has a crest portion, corresponding to a considerable portion of the abscissæ, and representing forces of attraction of equal values. Thus throughout 10 a considerable change of the distance between the bearing surface of the pressure member and the fixed solenoid, the attractive force remains practically constant, and no matter whether the pressure member dipping 15 into the pile of granules is located near down to the bottom of the granule chamber or up on a point of a stacked up pile of granules, the attraction of the armature and hence the pressure exerted by the said member 20 is, as nearly as necessary for practical purposes, proportional to the degree of magnetization of the solenoid. By the arrangement according to the invention the pile of granules, assembles around and beneath the 25 pressure plate, so that the pressure member is in a sense supported by the pile of granules, or so to speak, floats in the pile. The pressure plate can be made to assist this action if its dimensions taper away in the 30 direction receding from its pressing surface, a pyramid or core form of plate being thus specially suitable for the desired end. By this means, not only an easy trickling down of the granules and a reduction of their friction 35 against the plate is insured, but the additional advantage is obtained that, even when no pressure whatever is exerted by the plate and as long as it is not fully separated from the granules, the electrical resistance 40 of the pile can never become infinitely great, because, on account of the tapering form, portions of the pile of granules always remain in contact with the side surfaces of the plate, so that the circuit through the pile 45 of granules is never entirely interrupted. This circumstance contributes considerably toward the prevention of spasmodic regulating action.

The invention is illustrated in the accompanying drawing in which Figure 1 is a known graphical representation of the forces of attraction of a solenoid.

Fig. 2 is a diagrammatic sectional view of a solenoid and its connections with a dynamo 55 and

Fig. 3 shows a specific form of magnetic casing enveloping the solenoid.

In Fig. 1 the abscissæ a represent the distances of the center of gravity of the core 60 of the solenoid from the magnetic center of the solenoid. The ordinates indicate corresponding attractive forces of the solenoid. In the magnetic center M of the solenoid the force of attraction is zero, and it may be 65 assumed that this force drops again to zero

when the core has traveled a considerable distance away from the solenoid into the position N . Now if the core or armature moves between the points M and N the force of attraction increases as shown by the curve K , 70 until it reaches a maximum and then it drops gradually till it again reaches the zero point. It is known that the maximum force is exerted when the armature is approximately in the position shown in Fig. 2. It 75 will be seen that the crest portion of the curve is very flat, so that the maximum values of the forces of attraction change very little within the limits of movement of the armature, which are described by the distance a^1 . This section a^1 is therefore used for the travel of the armature. If the magnetization of the coil of the electro-magnet alters, the force of attraction will also change and, if graphically shown, it will, 80 for example, describe the curves K_2 , K_3 , K_4 but the crest portion of the curve will always be nearly flat, so that the section a^1 will appear as suitable for the various positions of travel of the armature. 85

The invention is exemplified in Fig. 2, in which a case is shown of a dynamo driven at varying speeds, and in which the potential of the machine is to be regulated so as to be maintained constant. The shunt winding b is therefore connected to the pressure plate c . This plate is pressed by a spring d , that is held by the support h , against the pile of granules e , which is inclosed in the chamber f . The bottom of the chamber f is 90 connected by the wire g to a terminal of the dynamo, the other terminal of the dynamo being connected to the other end of the field winding. The voltage at the machine terminals is applied to the winding of the 95 solenoid. The pressure plate c is coupled to the core or armature i by a rod of such length that the core lies in the zone of the maximum of attractive force of the solenoid. When the pressure plate c moves upward the granules trickle or roll down the cone surface of the plate, so that a pile of sufficient thickness will always accumulate 100 on the bottom of the chamber. 105

The general functions of such regulators 110 are sufficiently known and need not be described herein. If the granules pile up in any position whatever, the armature will follow the movements of the pile without leaving the zone of the solenoid in which, 115 assuming constancy of magnetization, its force of attraction remains practically equal.

In the modification shown in Fig. 3 the 120 solenoid is substituted by an electromagnet 125 of solenoid form. In the iron body l a winding h is inclosed and the core i is attracted most strongly in the section a^1 , the force of attraction altering considerably in positions higher or lower than this section. 130

In the claims the term "electric magnitude" will be used to denote "potential," "voltage," "current strength" etc.

I claim:

- 5 1. An automatic regulator for regulating an electric magnitude depending on an electric machine, comprising a relay with a coil to which said electric magnitude is applied, an alterable resistance consisting of a pile of 10 conducting bodies, and a pressure plate operatively connected to the armature of said relay and adapted to press upon said pile, said pressure plate tapering upwardly from the pressing surface so as to allow said conducting bodies to slide from its upper to the lower portions.
- 15 2. An automatic regulator for regulating an electric magnitude depending on an electric machine comprising a relay with a coil to which the said electric magnitude is applied, an alterable resistance consisting of a

pile of conducting granules, a pressure plate, 25 pressing means for pressing the said plate upon the said pile, an armature to the said coil, and a connection between the pressure plate and the said armature by which the armature is always kept in a zone of approximately constant attractive force, so as to produce alterations of the said resistance practically proportional to the electric magnitude applied to the said coil, the pressure plate tapering upward from the pressing surface of the pressure plate so as to allow the said granules to slide from its upper to its lower portions. 30

In testimony whereof I affix my signature in presence of two witnesses.

AUGUST KAZENMAIER.
